UNITED STATES PATENT OFFICE.

ARNOLD PFAU, OF MILWAUKEE, WISCONSIN, ASSIGNOR TO ALLEN-CHALMERS MANUFACTURING COMPANY, OF MILWAUKEE, WISCONSIN, A CORPORATION OF DELAWARE.

HYDRAULIC TURBINE.

Application filed March 31, 1922. Serial No. 548,543.

This invention relates in general to improvements in the art of hydraulics, and relates more specifically to improvements in the construction and operation of hydraulic turbines and the like.

An object of the invention is to provide a hydraulic turbine which is simple in construction and efficient in operation. Another object of the invention is to provide simple and compact means for preventing distortion of the casings of hydraulic machines which are operable under high pressures. A further object of the invention is to provide a direct and rigid cross connection between separated casing portions of hydraulic turbines, which may be subjected to relatively high fluid pressures. These and other objects and advantages of the present invention will be apparent from the accompanying specification.

A clear conception of several embodiments of the invention and of the operation of devices constructed in accordance therewith, may be had by referring to the drawings accompanying and forming a part of this specification, in which like reference characters designate the same or similar parts in the several views.

Fig. 1 is a longitudinal vertical section through a hydraulic turbine of the inward flow type.

Fig. 2 is an enlarged fragmentary sectional view through the turbine inlet mechanism.

Fig. 3 is an enlarged fragmentary sectional view through another form of turbine inlet mechanism.

Fig. 4 is an enlarged fragmentary sectional view showing the guide vane bearing structure and stay bolt.

The hydraulic turbine illustrated in Fig. 1 comprises in general an inward flow Francis turbine rotor 2 secured to a horizontal shaft 3 supported in bearings 19, 20, and enclosed within a casing comprising opposite side portions 8, 9, a speed ring 6, and a spiral inlet casing portion. The spiral inlet casing portion forms a high pressure fluid supply conduit 4 which communicates with the rotor 2 through the annular speed ring 6 and through the annular space between the casing side portions 8, 9. The turbine rotor 2 communicates with a discharge space 5 which in turn communicates with

the tail-race through a draft tube, in the usual manner.

The turbine inlet gate mechanism illustrated specifically in Figs. 2 and 4, comprises an annular series of adjustable guide vanes 7 having integral or rigidly connected hollow pivot stems 10. In the form of gate rigging shown in Figs. 1, 2 and 4, the side casing portion 9 is provided with a series of laterally and outwardly extending ears 15 each of which supports a bearing 18 spaced laterally from its supporting casing portion 9 and cooperating with an end of the hollow stem 10. The side casing portion 8 is likewise provided with a series of laterally and outwardly extending ears 16 each of which has a bearing 18 spaced laterally from its supporting casing portion 8 and cooperating with an end of the pivot stem 10. The casing portions 8, 9 are provided with stuffing boxes 13 adjacent to the stems 10, the bearings 18 being spaced from the casing portions 8, 9, sufficiently to permit removal and insertion of the stuffing boxes 13. A guide vane manipulating arm 11 is rigidly attached to each of the stems 10 adjacent to the bearing 18 supported in the adjacent ear 16. A stay bolt 12 passes through the hollow stem 10 of each guide vane 7 and is provided with opposite threaded ends adapted to receive nuts 14 coacting with stay plates 17 which in turn coat with the ears 15, 16. The stay plates 17 do not bear against the stems 10, as clearly shown in Fig. 4.

In the form of gate rigging illustrated in Fig. 3, the ears 25, 26 formed on the casing side portions 9, 8 respectively, project laterally and inwardly toward the axis of the turbine, rather than outwardly as illustrated in Fig. 2. In this embodiment of the invention, the ears 26 may be provided with openings through which the vane adjusting arms 11 extend, or the arms 11 may be directed inwardly thereby avoiding necessity of providing the holes in the ears 26.

During normal operation of the turbine, fluid under high pressure is delivered from the inlet or supply chamber 4 through the speed ring 6 to the spaces between the adjustable guide vanes 7. The guide vanes 7 deliver the fluid against the vanes of the rotor 2 wherein energy of the fluid is converted into torque in the rotating shaft 3.

The fluid delivered from the rotor 2 passes through the discharge chamber 5 and the draft tube, to the tail-race. The quantity of fluid admitted to the rotor 2 as well as the direction of flow of the fluid, is regulable by adjustment of the guide vanes 7, such adjustment being effected with the aid of the adjusting levers or arms 11. These adjusting arms 11 are ordinarily connected to a servo-motor controllable by a speed governor or otherwise.

It will be noted that as the high pressure fluid passes through the annular space between the side casing portions 8, 9, it tends to separate these casing portions and such action is ordinarily resisted only by the bolts which fasten the casing portions 8, 9 to the speed ring 6. By applying the stay bolts 12, within the adjusting stem 10 in addition to the fastening between the casing portions 8, 9 and the speed ring 6, a more direct and an additional union between the side casing portions 8, 9, is obtained. This direct union does not, however, interfere with efficient manipulation of the vanes 7 or with proper packing of the openings in the casing portions 8, 9, through which the stems 10 pass. The stuffing boxes 13 enable such proper packing and prevent undesirable escape of fluid, these stuffing boxes being readily accessible and manipulable from the exterior of the turbine casing. The stay bolts 12 moreover provide rigid supports or bearings for the adjusting stems 10 and prevent possibility of excessive distortion of these stems. As the stems 10 are subjected mainly to torsional strains, the openings through these stems do not materially weaken them. The stay bolts 12 are also readily removable at any time without interfering with the normal operation of the turbine, if such removal becomes desirable.

It should be understood that it is not desired to limit the invention to the exact details of construction and of operation herein shown and described, for various modifications within the scope of the claims may occur to persons skilled in the art.

It is claimed and desired to secure by Letters Patent:

1. In a turbine, a movable guide vane, a movable stem supporting said vane, and a stationary stay bolt longitudinally penetrating said movable stem, said stem functioning to support said vane independently of said stay bolt.

2. In a turbine, a guide vane, a hollow stem supporting said guide vane, means associated with said stem for adjusting said guide vane, and a stay bolt extending through said vane adjusting means and said stem, said stay bolt being free from contact with said stem.

3. In a turbine, a casing comprising spaced stationary portions, a guide vane lo-

cated within said casing, a hollow stem secured to said vane and pivotally supported in said casing portions, means for moving said stem to adjust said guide vane, and a stationary member passing through said stem and rigidly uniting said casing portions.

4. In a hydraulic turbine, a rotor, a source of high pressure fluid supply, a movable guide vane between said source and said rotor, a casing comprising independent portions located on opposite sides of said guide vane, means for pivotally supporting said guide vane in said casing, and a tension member passing freely through said guide vane and rigidly uniting the portions of said casing on opposite sides of said vane.

5. In a hydraulic turbine, a casing forming a conduit, a guide vane in said conduit, said casing having ears extending away from and located on opposite sides of said guide vane, means coacting with said ears to pivotally support said guide vane, and means coacting with said casing and with said pivotal supporting means to prevent escape of fluid from said casing, said escape preventing means being located between said ears and said guide vane.

6. In a hydraulic turbine, a rotor, a guide vane for conducting fluid to said rotor, a casing comprising independent portions located on opposite sides of said guide vane and of said rotor, each of said casing portions having a bearing spaced outwardly therefrom, pivots for said vane coacting with said bearings, stuffing boxes for preventing escape of fluid along said pivots, and means between one of said bearings and the adjacent casing portion for adjusting said guide vane.

7. In a hydraulic machine, a rotor, a casing forming a conduit communicating with said rotor, an adjustable guide vane for controlling the flow of fluid through said conduit, a pivot supporting said vane, and an element extending through said pivot and acting independently thereof for rigidly uniting portions of said casing on opposite sides of said vane.

8. In a hydraulic machine, a casing comprising spaced portions, a guide vane located within said casing, a hollow stem forming a support for said guide vane, means for moving said stem to adjust said vane, and a member passing through said stem and rigidly uniting said casing portions.

9. In a hydraulic turbine, a casing forming a conduit, a guide vane in said conduit, a pivot for said vane, mechanism for moving said vane through said pivot, and means acting independently of said pivot for directly connecting the portions of said casing on opposite sides of said conduit.

10. In a hydraulic turbine, a casing forming a conduit, a guide vane in said conduit,

a pivot supporting said vane and projecting outwardly beyond said casing, mechanism located outside of said casing for moving said vane through said pivot, and means located within said pivot for connecting the portions of said casing on opposite sides of said conduit.

11. The combination with a casing of a hydraulic turbine including oppositely disposed side plates, of a wicket gate having trunnions projecting from the ends thereof and rotatably seated in said plates, the gate and trunnions having alined bores therethrough, and a pin loosely inserted through the gate and trunnion bores and fixed to the plates.

12. A hydraulic turbine comprising oppositely disposed side plates having sockets therein, a wicket gate having trunnions movably extending into the said sockets, renewable bushings mounted in the sockets

around the trunnions, and a pin loosely extending through the gate and trunnions and fixed at its opposite extremities to the plates.

13. A wicket gate for a hydraulic turbine 25 having trunnions projecting from the opposite ends thereof, the trunnions and gate having alined bores therethrough, combined with a fixed axis device extending through the trunnions and gate on which the latter 30 have pivotal movement.

14. A hydraulic turbine casing having gate supporting members, a wicket gate having trunnions at opposite ends movably extending into portions of the members, and a pin loosely extending through the trunnions and gate and secured to said members and enclosed and shielded from water contact.

In testimony whereof, the signature of the 40 inventor is affixed hereto.

ARNOLD PFAU.
